CLAIM

The ornamental design for an infant lozenge medication administering pacifier, as shown and described.

DESCRIPTION

FIG. 1 is a perspective of an infant lozenge medication administering pacifier, showing my new design;

FIG. 2 is a top plan view thereof;

FIG. 3 is a bottom plan view thereof;

FIG. 4 is a left side elevational view thereof, the right side elevational view being a mirror image;

FIG. 5 is a front elevational view thereof; and,

FIG. 6 is a back elevational view thereof.
